UNITED STATES PATENT OFFICE.

WALTER G. TRAUTMAN, OF CLEVELAND, OHIO.

MASSAGE-MACHINE.

968,209.

Specification of Letters Patent. Patented Aug. 23, 1910.

Application filed March 28, 1910. Serial No. 551,957.

To all whom it may concern:

Be it known that I, WALTER G. TRAUTMAN, a citizen of the United States, residing at Cleveland, in the county of Cuyahoga and State of Ohio, have invented certain new and useful Improvements in Massage-Machines, of which the following is a specification.

My invention relates to improvements in so-called vibrators or massage machines, and the invention consists in certain novel and original constructions and combinations of parts which materially contribute to the utility and convenience of such machines in which varying strokes or throw of the applicator are provided for and there is perfect control and adjustment of all strokes by convenient means on the outside of the machine, all as hereinafter fully described and particularly pointed out in the claims.

In the accompanying drawings, Figure 1 is a side elevation of my improved machine partially sectioned in its operating parts. Fig. 2 is a side elevation of the extension of the machine in which said operating parts are located, and Fig. 3 is a sectional elevation thereof showing the position of the operating parts adjusted as compared with Fig. 1. Fig. 4 is a cross section on line $x-x$, Fig. 1, and Fig. 5 is a perspective detail of the split spring ring. Figs. 6 and 7 represent sectional elevations of modifications of the invention as hereinafter fully described. Fig. 8 is a plan view of the spring shown in Figs. 6 and 7.

In these several views C represents the casing or shell for the electrical motor (not shown) and is provided with a neck c at what may be regarded as its bottom and a handle c' at its side as usual. An adjusting tube B is threaded in the said neck and the operating mechanism is mounted on or housed in said tube as will presently appear. The measure or extent of said adjustment is seen by comparison in Figs. 1 and 3, the full limit of inward adjustment being shown in Fig. 1 and the outward adjustment in Fig. 3. Both adjustments are effected by merely turning the said tube inward or outward on its thread 2 in neck c, and in any case after such adjustment is made the said tube is locked on neck c by the nut N. Said neck has its end split and externally threaded and beveled at its lower edge 3, and the clamping ring shaped nut N about said split extension has an inner beveled or

flanged portion 4 at its bottom adapted to engage said beveled edge 3 and force the split end of the neck into clamping relations upon the tube B and lock it against rotation. 60 The said tube B itself is split at 5 in its outer end so as to give it something of a spring action in connection with the bearing screws 6 therein, and the applicator A is suspended from within this split portion on 65 a split ring R supported oppositely or at two points by conical pointed bearing screws 6 and on which said ring is adapted to rock more or less in the operation of the applicator.

In Figs. 1 to 4 inclusive the applicator is shown as having a headed spindle H separably connected therewith and provided with a relatively reduced stem 7 projected into a sleeve 8 through which operating connections are made with the shaft S of the electric motor. The said stem 7 fits closely in said sleeve but is rotatably free therein and has a head 9 provided with opposite pivot cavities engaged by the points of pivot 80 screws 10 through ring R at right angles to the screws 6 supporting said ring. The applicator is disengaged from said head 9 in Fig. 3, and in relation of said screws 6 and 10 are shown in Fig. 4.

The motor or armature shaft S by which the machine is driven has an eccentrically set pin 12 at its end straight with said shaft in its inner half and laterally inclined thereto at an obtuse angle in its outer half d 90 relatively as shown, and the head 14 of sleeve 8 has a correspondingly inclined hole or bore 15 in its top through which said inclined portion of crank stem 12 extends more or less according to the working relations 95 of the parts under the adjustments hereinbefore described of tube B. Thus, if the said tube be adjusted inward, the applicator shaft comprising parts H and 8 will also be moved inward and thrown to inclination 100 proportioned to such adjustment by sliding upward on inclined end d of stem 12. The maximum adjustment inward is shown in Fig. 1, and in this position the applicator gets its greatest throw and is automatically 105 slowed in proportion to the throw by the greater pull it causes on the motor. On the other hand when the minimum adjustment of the parts is made by throwing tube B outward as in Fig. 3 the parts are brought 110 more nearly into alinement and the applicator has its least throw or gyration. The

measure or degree of gyration or throw can thus be changed through tube B, and as the throw is decreased the strokes or gyrations of the applicator are increased to the same extent by reason of the lighter work on the motor.

In the form of invention, Figs. 1 and 3, a spiral spring 16 is engaged about the upper portion of crank stem 12 between the end 10 of shaft S and head 14 of the sleeve 8 and affords a yielding pressure as between said head and said shaft which accommodates itself to all positions and operations of the immediately associated parts. The recess 15 15 in the top of head 14 for the angle of stem 12 has its bottom in line with the inclined hole through the head for part d of stem 12, so that the angle of said stem may be accommodated to varying positions therein between Figs. 1 and 3 in making the adjustments above set forth. A light washer 20 rests the spring 16 on the head 14.

The bearing ring R is shown and described as a split spring ring, and the spring 25 tendency thereof is inward toward screws 10, so that it will take up any wear that may come in the bearing cavities for said screws. The ring R therefore rocks more or less on its bearings while the vibrator shaft or 30 spindle comprising the parts H and 8, is supported and rocks on the pivot screws 6, thus in effect making a universal joint.

Fig. 6 represents an important modification of the invention and in some respects is 35 the reverse of Fig. 1. Thus in this view the applicator spindle 24 has an axial bore adapted to receive a stem 30 which in a sense substitutes stem 12 in Fig. 1. This stem has a compound bend beginning with 40 an offset 31 parallel to the body of the stem and having an outwardly inclined straight extremity 32 which passes through a similarly inclined bore or hole in the end of motor shaft S, with a recess behind said 45 bore to permit the said stem to be thrown down and outward in respect to shaft S to effect adjustments and throw or stroke of applicator more or less as hereinbefore described. In this case, however, a spring 36 50 fashioned as seen in Fig. 8 is employed instead of spiral spring 16. This spring has a band shaped head sleeved over shaft S, and a recurved spring portion divided past the end of said shaft and bearing upon stem 55 32 at d'. The bend of this spring is shown at d'. In this construction of parts the maximum stroke of the applicator is obtained by turning tube B inward and the bearing of spring on the stem 32 tends to throw the 60 applicator shaft and the motor shaft more nearly in alinement as said tube B is more fully withdrawn.

Another modification is shown in Fig. 7. Here the crank pin 12 is set centrally in 65 shaft S, and the sleeve 8 is substantially the

same as in Fig. 1 but spring 36 is shown instead of spiral spring 16, although in fact either form of spring will work with this construction or with that shown in Fig. 1. In this case inward adjustment of tube B 70 reduces eccentricity of throw of the applicator, which is just the reverse of Fig. 1, and the spring 30 is mounted on sleeve 8 instead of shaft S, and bears against the inclined end d of crank stem 12.

It has been observed that a spreading effect is obtained by the spring interposed between the motor shaft and the applicator shaft members, whether it be spring 16 or 36. In one case the spring is immediately 75 between said shafts and in the others the location of the spring is different but the effect is the same and a tension part of member serving the purposes of said spring is functionally indispensable in my machine.

These several different views of the invention serve to show practical variations of the machine in the particulars they cover, and still further modifications might be suggested to give a still wider range to the principle involved, but the disclosures made are believed to be sufficient to show what the range of the invention really is as well as the essentials of its details.

In Fig. 6 the intermediate member or 95 sleeve 8 shown in the other views is omitted and the stem 31 is loosely or rotatably mounted in spindle 24 and constitutes a portion of the so-called applicator shaft, and also has the crank by which the eccentric positions 100 of the applicator are fixed integral with its upper portion rather than being integral with shaft S. This, however, represents difference in construction and not in operative effect or function.

The spring tension developed in the parts 105 16 and 36 respectively varies with the angle at which the applicator is adjusted to work and according to the angle or eccentricity of the applicator as compared with the fixed 110 alinement of the motor shaft, as plainly illustrated in Figs. 1 and 3, but the essential function of the spring in any case is to hold the member 8 or 30 on which it bears to its seat and thus make said member the same 115 as unitary with the applicator spindle though it does revolve thereon or therein and also hold the adjustments of the crank stem at whatever angle it may be set by the adjusting mechanism.

What I claim is:

1. In a machine of the class described, a motor shaft, an applicator spindle, a crank connection between said shaft and spindle comprising a part having a laterally inclined bore and a laterally inclined crank stem slidably confined without rotation in said bore, a fulcrum support for said spindle movably related to said shaft to change the angle of inclination of said spindle, and 125 130

means mounted upon one of said elements to hold the crank connection parts in constant working engagement regardless of adjustments.

5. 2. In a machine of the class described, an applicator spindle adapted to gyrate, a rotary power shaft, a member rotatively engaged with said spindle having a laterally inclined portion slidably engaged to rotate 10 with said power shaft, means to bring the applicator spindle nearer to or farther from said shaft, and a spring tension device adapted to hold said member and spindle in seated working relations and in different 15 working angles in respect to said shaft.

3. In a machine of the class described, a power shaft, an applicator spindle, a member rotatably sleeved upon said spindle, and said shaft and rotatable member having 20 laterally inclined portions slidably engaged and connected to rotate together without independent rotation, and a spring intervening said parts to hold said member under compression, in combination with an adjustable 25 rocking support for said applicator spindle adapting axial adjustments thereof relatively to said power shaft to change the working angles of said spindle.

4. In a machine of the class described, a power shaft having a crank stem laterally inclined in respect thereto, an applicator spindle having a fulcrum support movable 30 axially in respect to said shaft, a sleeve rotatively mounted upon said spindle having 35 an inclined portion slidably connected with said crank stem, and a spring mounted between said sleeve and shaft to hold the sleeve upon the stem in any adjusted position of the spindle in respect to said crank stem.

40 5. In machine of the class described, an applicator and a two-part shaft therefor having one part rotatable in respect to the other, a universal joint support for said shaft comprising a split spring ring having rocking 45 bearings and rocking bearings for said shaft in said ring, and a power shaft having an adjustable crank connection with said applicator shaft.

6. In a machine of the class described, a main casing and a power shaft therein, and 50 a tubular member adjustable toward and from said casing, an applicator shaft mounted in and adjustable with said member and having a crank connection with said power shaft adapted to change the angle of inclination of the applicator shaft, a split spring ring having rocking bearings supporting 55 said applicator shaft and rocking bearings in said tubular member supporting said ring, said casing having a split extension in which 60 said ring is mounted.

7. In a machine of the class described, a main casing and an applicator shaft, a tube of spring metal on said casing split in its outer end, a split bearing ring of spring 65 metal in the split end of said tube, conical bearing screws oppositely in said tube providing rocking bearings for said nut and conical bearing screws at right angles to said other screws providing rocking bear- 70 ings for said applicator shaft.

8. In a machine of the class described, a power shaft and an applicator shaft, means connecting said parts adapted to gyrate said applicator shaft, and a universal joint for 75 said applicator shaft comprising a split ring of spring metal having a pivoted connection with said applicator shaft and an expansible and contractible support having a pivoted connection with said ring. 80

9. In a machine of the class described, a power shaft and a gyratory applicator support operatively connected therewith, and a universal joint connection for said support comprising a split tension member adapted 85 to spring inwardly having pivot engagement with said support, and a split tension holder adapted to spring inwardly having pivot connections for said member.

In testimony whereof I affix my signature 90 in presence of two witnesses.

WALTER G. TRAUTMAN.
